UNITED STATES PATENT OFFICE

107,160

DESIGN FOR A GAME BOARD

Alton Schuster, Toledo, Ohio

Application May 24, 1937, Serial No. 69,528

Term of patent 3½ years

To all whom it may concern:

Be it known that I, Alton Schuster, a citizen of the United States and resident of Toledo, county of Lucas, State of Ohio, have invented a new, original, and ornamental Design for a Game Board, of which the following is a specification, reference being had to the accompanying drawing, forming a part thereof.

The figure is a plan view of the game board, showing my new design. The game board has no appreciable thickness.

I claim:

The ornamental design for a game board substantially as shown and described.

ALTON SCHUSTER.
